DRIVE RING

John Karitzky, Cranford, N. J., assignor to Diamond Expansion Bolt Company, Inc., Garwood, N. J., a corporation of New Jersey

Application October 24, 1950, Serial No. 191,770

2 Claims. (Cl. 248—71)

1

This invention relates to an improved drive ring of the type used by electricians, for example, to hang wires or cables to supporting surfaces.

Drive rings of the type here under consideration are, in general, well known and have been used for many years for different types of electrical installations. It is prerequisite for many jobs that the drive ring be galvanized so as to be able to withstand the corrosive effects of high humidity or other factors obtaining at the place of installation. It has been found that in commercially available drive rings a small chip of the galvanizing material forms between the eyelet of the ring and the collar of the nail when the ring and nail are assembled. When the mechanic drives the drive ring into its supporting position, his repeated hammer blows frequently dislodge this chip, and not infrequently the chip flies into the mechanic's face, sometimes injuring his eyes. It is accordingly among the objects of this invention to provide an improved drive ring which obviates the foregoing disadvantage, among others.

In the drawing, wherein are shown three possible embodiments of my invention,

Figure 1 is a perspective view of the drive ring; Figure 2 is an enlarged top plan view of the drive ring;

Figure 3 is an enlarged bottom plan view of the drive ring;

Figure 4 is an enlarged elevation of the nail member of the drive ring;

Figure 5 is an enlarged fragmentary elevation of a modified form of nail member;

Figure 6 is a horizontal section taken along the line 6—6 of Figure 5;

Figure 7 is an enlarged fragmentary elevation of another form of nail member; and,

Figure 8 is a horizontal section taken along the line 8—8 of Fig. 7.

Similar reference characters refer to similar parts throughout the views of the drawing.

In accordance with one embodiment of my invention, the drive ring comprises a generally U-shaped member or loop, one end of which is bent to form an eyelet through which the nail member of the drive ring is forced. This nail member includes a collar, preferably nearer one end of the nail than the other, and between this collar and the pointed end of the nail, the shank of the nail is slightly enlarged to a diameter slightly greater than the diameter of the eyelet on the loop. The rest of the nail shank is of substantially the same diameter, or perhaps of slightly smaller diameter than the eyelet. Thus the

5 nail may be slid freely through the eyelet until its enlarged shank portion enters the eyelet. This portion is then forced into the eyelet, but it is of such short axial length that there is insufficient galvanizing material to gather together and form a chip between the eyelet and the collar when the collar is firmly seated against the eyelet.

Referring now to Figure 1 of the drawing, the 10 drive ring comprises a generally U-shaped member or loop, generally indicated at 10, having an eyelet 11 formed on one end thereof, through which a nail, generally indicated at 12, extends. Loop 10 comprises two legs 13 and 14 joined by a 15 base 15, eyelet 11 being formed on the end of leg 13. The diameter of the eyelet is preferably held within relatively narrow tolerances, and may have for example, diameter of .130 in.

Still referring to Figure 1, leg 14 of loop 10 is 20 bent inwardly somewhat toward leg 13 but, as shown in Figure 2, out of a vertical plane passing through leg 13. Thus, the loop legs 13 and 14 make installation of the wire or cable to be suspended by the drive ring a very simple matter, as such cable can either be threaded through the 25 loop or can be passed between leg 14 and the outer end 12a of nail 12, as is desired or expedited. In other words, with leg 14 bent as described, an access opening 16 (Figures 2 and 3) between leg 14 and nail end 12a is provided for the ready reception of a wire or cable not thicker than the dimension of this opening. The opening accordingly greatly facilitates the suspension 30 of the wire or cable, and also advantageously displaces the free end of leg 14 of the eyelet from the nail head 12a which is to be struck by a hammer when driven into the wall.

As shown in Figure 4, nail 12 includes a pointed 35 end 12b and a collar 17 which is preferably positioned nearer the nail head 12a than the pointed end 12b. Adjacent collar 17 the shank 40 of the nail is slightly enlarged, as at 18, and preferably includes a tapering portion 18a which varies in thickness from the diameter of portion 45 18 to the diameter of the nail shank. For example, if the nail shank measures .120 in. in diameter, enlarged portion 18 may advantageously have a diameter of .130 in. Of course, the difference in diameter of the nail shank and portion 18 may be varied within reasonable limits, depending on particular conditions, or different sizes of drive rings.

Prior to assembly of loop 10 and nail 12, the 50 two parts are galvanized in a customary manner. This, of course, decreases somewhat the diameter

of eyelet 11, and increases somewhat the diameter of the nail shank and also its enlarged portion 18. These diameter variations, however, are not sufficient to preclude the ready insertion of the pointed end of the nail in the eyelet during the first assembly step. The pointed end 12b of the nail, and the following shank sections thereof, accordingly may be slid readily through eyelet 11 until the taper 18a of enlarged portion 18 is reached. As the diameter of portion 18 will be slightly greater than that of the eyelet, this portion of the nail must be forced through the eyelet until collar 17 rests or abuts thereagainst. Inasmuch as the axial length of enlarged nail portion 18 preferably approximates the thickness of the wire forming eyelet 11, however, only approximately one-half of the enlarged portion will be engaged by the inner diameter of the eyelet during the final assembly operation. The extent of this engagement is so slight that no chip of galvanizing material will form, but yet the nail and eyelet are securely held together.

With the nail 12 and loop 10 thus assembled, it will be seen (Figure 1) that loop leg 13 extends substantially at right angles to nail 12, while loop leg 14 is directed somewhat inwardly toward eyelet 11 and is accordingly not parallel to leg 13. This feature, together with the bent-over characteristic of leg 14, as best shown in Figures 2 and 3, provides a highly efficient loop or ring for the reception and retention of the wire or cable. Furthermore, when the electrician installs the drive ring, there is nothing in the immediate vicinity of the nail head 12a to impede or deflect his hammer blows, and accordingly the drive ring may easily be driven into the supporting surface without danger of bending the loop from the hammer blows, or without danger of any galvanizing chip striking the mechanic.

In Figures 5 and 6, wherein a modified form of the drive ring is shown, nail 12 is provided with an enlarged portion 19, which enlargement is formed as by knurling that portion of the nail shank adjacent collar 17. This type of enlargement has certain advantages under given conditions, and upon being forced through the loop eyelet, effectively maintains the loop and nail in properly related assembly.

Still another manner of forming the enlarged nail portion is shown in Figures 7 and 8. As shown in Figure 7, an enlarged portion 20 may be formed by scoring or grooving that portion of the nail shank adjacent collar 17 by a suitable tool to form valleys 21 and adjacent ridges 22, these ridges extending beyond the diameter of the

nail shank, and accordingly forming the characteristic enlargement which, when forced through the loop eyelet, maintains the parts in properly related assembly.

Accordingly it may be seen that I have provided a drive ring which attains the several objects set forth in a thoroughly practical and efficient manner.

I claim:

1. A drive ring having one end thereof bent back on itself to form an eyelet, and a nail extendable through said eyelet, said nail being thickened at a portion spaced from its pointed end to a dimension slightly larger than the dimension of said eyelet, that portion of the nail between its thickened portion and its pointed end having substantially the same diameter as said eyelet, whereby the nail may be easily slid through said eyelet to said thickened portion and the thickened portion thereafter forced into said eyelet to retain said eyelet and nail in assembled relation, at least the thickened portion of said nail being galvanized.

2. A drive ring having one end thereof bent back on itself to form an eyelet, a nail extendable through said eyelet, said nail being thickened at a portion spaced from its pointed end to a dimension slightly larger than the dimension of said eyelet, that portion of the nail between its thickened portion and its pointed end having substantially the same diameter as said eyelet, whereby the nail may be easily slid through said eyelet to said thickened portion and the thickened portion thereafter forced into said eyelet to retain said eyelet and nail in assembled relation, at least the thickened portion of said nail being galvanized, and a stop collar on said nail at the outer end of said thickened portion to limit passage of said nail through said eyelet.

JOHN KARITZKY.
